UNITED STATES PATENT OFFICE.

RALPH H. UPSON, OF AKRON, OHIO, ASSIGNOR TO THE GOODYEAR TIRE & RUBBER COMPANY, OF AKRON, OHIO, A CORPORATION OF OHIO.

ENGINE-HOOD AND RADIATOR COVER.

1,327,891.

Specification of Letters Patent. Patented Jan. 13, 1920.

Application filed July 20, 1918. Serial No. 245,941.

To all whom it may concern:

Be it known that I, RALPH H. UPSON, a citizen of the United States, and resident of Akron, Ohio, have invented new and useful 5 Improvements in Engine-Hood and Radiator Covers, of which the following is a specification.

My present invention relates broadly to new and useful improvements in covers for 10 engine hoods and radiators, and has particular reference to improvements in covers of this character used in connection with air craft engines.

With reference to the drawing wherein 15 there has been illustrated a preferred embodiment of the invention as it is reduced to practice, and throughout the several views of which, similar reference numbers designate corresponding parts:

20 Figure 1 is a perspective view of my improved cover;

Fig. 2 is a front elevation of same;

Fig. 3 is a side elevation of same; and

Fig. 4 is a section on line 4—4 of Figs.

25 1 and 3.

In the drawing the numeral 10 designates 30 the main body of the cover, which is preferably formed from sheets of rubberized fabric and lined on the inside with several layers or plies of felt, or the equivalent heat 35 insulating material. At certain portions of the cover sheet asbestos is applied to the inside face of these felt layers to prevent the exposed and hottest portions of the engine from scorching or otherwise injuring the 40 cover.

The location of the asbestos sheet will, of course, vary in accordance with the design of the engine to which the hood is applied.

45 An opening 11 is, of course, provided in the forward end of the body portion of the cover to accommodate the radiator cap, and attaching straps having snap fasteners, as at 12, are provided at the longitudinal edge of the body of the cover as a means for attaching same to the engine hood.

A front wall portion or piece 13, is sewed or otherwise attached to the front edge portion of the body portion 10, the front edge portion of the body 10 being lapped over the edges of the front portion 13, as shown at 50 10". Notches 11" are formed for a suitable distance in the front edge portion of the body 10, to permit the edge more readily to

conform to the shape of the front portion 13, 55 and a binding strip 13' is utilized to further secure the body 10 about the front portion 13. An opening 14 is provided in the front portion 13, to receive the propeller shaft and the front portion is bifurcated as indicated at 15, to permit the propeller shaft to be received in the opening 14.

The two flaps 16 and 17, which result from the bifurcation, are connected to each other when the cover is applied to the engine 60 hood, by a strap 18 and snap fasteners or the equivalent 19.

As a means for insuring that the flaps 16 and 17 will remain flat and in contact with the radiator and not interfere with the propeller shaft, two metal strips or rods 20 are applied to the members 16 and 17 on each side of the bifurcation, as illustrated in Fig. 1. These metal strips may be inserted between the plies or may be attached to the 75 outside of the flaps or to the inside thereof, this being purely a matter of design.

It will of course be understood that, while I have described my present engine cover as being particularly designed for air craft engines, it may nevertheless be employed with equal efficiency in connection with the engine of any other vehicle, without departing in any way from the spirit of the invention or the scope of the appended claims. 80

What I claim is:

1. An engine cover comprising a body portion, means for attaching the body portion in applied position over the hood of the engine, a front wall portion attached to the body portion and provided with an opening to accommodate the shaft of the engine, said front wall being slit from said opening to its lower edge producing two depending flaps, means for detachably connecting said flaps, and stiffening elements located on opposite sides of the slit for holding the flaps flat against the radiator. 95

2. An engine cover comprising a body portion, means for attaching the body portion in applied position over the hood of the engine, a front wall portion attached to the body portion and covering the radiator of the engine, said front wall portion having an opening to accommodate the shaft of the engine and being slit from said opening to its lower edge producing two depending flaps, means for detachably connecting said flaps, 100 105

- flaps, and parallel metal strips applied to the flaps on opposite sides of the slit for holding the flaps flat against the radiator.
3. An engine cover comprising a body portion composed of an outer sheet of water proof fabric lined on the inside with felt, a front wall attached to the body portion and having a slit producing depending flaps, means for detachably connecting said flaps, and stiffening elements disposed on said front wall at opposite sides of the slit.
4. An engine cover comprising a body portion composed of an outer sheet of water proof fabric lined on the inside with felt, and asbestos applied to a portion of said felt, a front wall attached to the body portion and having a slit producing depending flaps, means for detachably connecting said flaps, and stiffening elements disposed on said front wall at opposite sides of the slit.
5. An engine cover comprising a body portion composed of an outer sheet of water proof fabric lined on the inside with felt, and asbestos applied to a portion of said felt, a front wall portion attached to the body portion and provided with an opening for the engine shaft, and a slit extending downwardly from said opening and producing depending flaps, means for detachably connecting said flaps, and stiffening elements disposed on the front wall portion at opposite sides of said slit.

In witness whereof, I have hereunto signed my name in the presence of two subscribing witnesses.

RALPH H. UPSON.
